UNITED STATES PATENT OFFICE.

CHARLES CHEERS WAKEFIELD, OF LONDON, ENGLAND.

WATER-GAGE COCK.

SPECIFICATION forming part of Letters Patent No. 743,354, dated November 3, 1903.

Application filed March 30, 1903. Serial No. 150,242. (No model.)

To all whom it may concern:

Be it known that I, CHARLES CHEERS WAKEFIELD, a subject of the King of England, residing at London, England, have invented 5 certain new and useful Improvements in Water-Gage Cocks, of which the following is a specification.

This invention is for improvements in water-gage cocks, and has for its object to provide means by which in the event of the gage-glass breaking the cocks communicating with the boiler may automatically close.

According to this invention valves normally open, but adapted to close against the admission of steam or water, are provided at each end of the gage-glass, and with these is combined a test-valve normally maintained closed by the pressure of steam in the gage. Connection is made between the gage-valve 20 and the test-valve, so that as long as this valve remains closed the gage-valves will be maintained open, notwithstanding fluctuations which may take place in the steam-pressure; but the moment the pressure is removed 25 from the test-valve by fracture of the gage-glass the gage-valves are freed and close against the admission of steam or water to the gage-glass.

In the accompanying drawings, Figure 1 is 30 a side elevation of a gage-cock in part section, constructed according to one method of carrying out this invention. Fig. 2 is a front elevation of the same, also in part section; and Fig. 3 is a plan of a detail.

Like letters indicate like parts throughout the accompanying drawings.

The gage-glass A is carried in mounts or brasses B at each end, each mount being provided with a gland B' of any convenient construction to prevent leakage at the point where the glass enters the mount. Each mount is hollow and is provided with a base or flange B², by which it may be secured to the boiler, and the base is perforated at B³ to admit steam or water from the boiler to the interior of the mount.

Within each mount B and interposed between the gage-glass and the orifice B³ is a barrel C. The barrels are open at one end, 50 which faces the boiler, and are perforated at C², so that fluid can pass from the boiler through the barrels to the gage-glass. Each

barrel is preferably formed integral with a hexagonal nut or head C' and screwed into place, so that it may be readily removed for 55 examination or repair. The open end of each barrel is controlled by a mushroom-valve D, adapted to close against the passage of fluid from the boiler to the gage-glass. These inlet-valves D are carried by spindles D', supported at one end in the base B² of their respective mounts and extended at the other end through the barrel and beyond the mount. A gland D² is provided at that end of each barrel remote from the boiler. This gland 60 supports the free end of the valve-spindle and prevents leakage between it and the barrel C. Each valve-spindle D' is cut away at D⁴ D⁵ to permit the free passage of fluid from the boiler to the interior of the barrel C, and 70 thus to the gage-glass A when the valves D are open.

Secured to each mount B is an arm E. (Shown in plan, Fig. 3.) Each arm carries at its free end a bearing E' to receive a shaft F. 75 The shaft F is free to be partially rotated in its bearings by means of a hand-wheel F', conveniently secured at the upper end, and arms or levers F² are secured to the shaft, the free end of each arm F² entering a slot or orifice 80 D⁶, one in each of the valve-spindles D', so that each valve is thus operatively connected with the shaft F. To the lower mount B is secured a valve-box G, provided with a barrel H similar to the barrel C in the mounts B. This 85 barrel is interposed between the gage-glass and its outlet-passage K, by which the contents of the glass can be discharged. The open end of the barrel communicates with the interior of the gage-glass, but is controlled by 90 a mushroom-valve J. The barrel H is perforated at H', so that its interior communicates with the discharge or outlet passage K. The spindle J' of the valve J extends through the barrel H and is carried in a gland 95 J² in a similar manner to the spindles D' of the valves D. The shaft F carries a third arm or lever L, the free end of which enters a slot or orifice J³ in the valve-spindle J', so that this valve is thus operatively connected 100 with the shaft F. The levers F² and L are so disposed upon the shaft F relatively to their respective valves that when the blow-off or outlet valve J is closed the inlet-valves D are open.

The operation of this device is as follows: Should the inlet-valves D be closed, the shaft F is partially rotated by means of its hand-wheel F', so that the inlet-valves are opened 5 and the outlet-valve J consequently closed. Steam and water then enter the gage-glass A through the perforations B³ in the mounts B, the open ends of the barrels C, and the perforations C². This admission of steam to the 10 gage-glass creates a pressure within the same which bears upon the outlet-valve J and maintains this valve closed, while there is practically no tendency to close the inlet-valves D, as the conditions are practically 15 static with the exception of a slight interchange of steam and water due to condensation within the gage-glass. Should, however, the gage-glass A be fractured by any means, the outlet-valve J is immediately relieved of 20 the pressure, and the rush of fluid from the boiler through each of the mounts B immediately drives the valves D back upon the ends of the barrels C, so that communication between the boiler and the gage-glass is cut 25 off. Sufficient play is allowed the inlet-valves D, so that the outlet-valve J may be opened by partially rotating the shaft F by hand without closing the valves D. This permits any sediment collected in the gage-glass to be 30 blown out through the outlet-passage K. To insure that the valves D shall not close through any surging of the steam or water without fracture of the gage-glass, the area of the valve J upon which the pressure within 35 the gage-glass is exerted is preferably made equal to or greater than the sum of the areas of the valves D.

It will be seen that by means of this invention a fractured gage-glass may be readily removed and a new one inserted without disturbing the connection between the mounts and the boiler.

By connecting the valves D and J with the shaft F and adapting the latter to be operated 45 by hand all three valves are moved when the valve J is opened for the purpose of blowing through the gage-glass. This results in these valves being always kept free, so that they do not stick and fail to come into operation 50 should the gage-glass A break, which is a point of great utility, as many of the safety devices at present in use fail to operate when required through their remaining in one position for such a length of time that they become rigidly fixed.

What I claim as my invention, and desire to secure by Letters Patent, is—

1. In a water-gage for a boiler the combination of a gage-glass, mounts for the ends of 60 the glass each having an inlet communicating with the interior of the glass and the boiler, a valve controlling each inlet and adapted to close against the passage of fluid from the boiler, a body adapted to be displaced by 65 the pressure in the gage, a stop to limit the amount of displacement and means operatively connecting this body with the valves

so that when the former is displaced the valves are held open, as set forth.

2. In a water-gage for a boiler the combination of a gage-glass, mounts for the ends of 70 the gage-glass each having an inlet communicating with the interior of the glass and the boiler, a valve controlling each inlet and adapted to close automatically against the 75 passage of fluid from the boiler, a valve controlling an outlet from the gage-glass the valve being adapted to close against pressure within the glass, and means for operatively connecting this valve with those which control the 80 inlets so that when the former is closed the latter are held open, as set forth.

3. In a water-gage for a boiler the combination of a gage-glass, mounts for the ends of 85 the gage-glass each having an inlet communicating with the interior of the glass and the boiler, a valve controlling each inlet and adapted to close against the passage of fluid from the boiler, a sliding spindle to each valve projecting through the mount, means to prevent 90 leakage between the spindle and the mount, a valve controlling an outlet from the gage-glass the valve being adapted to close against pressure within the glass, a sliding spindle to this valve, and means for operatively connecting the spindle of this valve 95 with those of the inlet-valves so that when the outlet-valve is closed the inlet-valves are held open, as set forth.

4. In a water-gage for a boiler the combination of a gage-glass, mounts for the ends of 100 the gage-glass each having an inlet communicating with the interior of the glass and the boiler, a valve controlling each inlet and adapted to close automatically against the 105 passage of fluid from the boiler, a valve controlling an outlet from the gage-glass the valve being adapted to close against pressure within the glass, means for operatively connecting this valve with the inlet-valves so 110 that when the outlet-valve is closed the inlet-valves are held open and vice versa, and means for controlling the movement of the outlet-valve independently of the pressure in the gage-glass, as set forth.

5. In a water-gage for a boiler, the combination of a gage-glass, mounts for the ends of 115 the gage-glass each having an inlet communicating with the interior of the glass and the boiler, a valve controlling each inlet and adapted to close against the passage of fluid from the boiler, a sliding spindle to each valve projecting through the mount radially to the gage-glass, means to prevent leakage between the spindle and the mount, a valve controlling an outlet from the gage-glass, the valve being adapted to close against pressure within the glass, a sliding spindle to this valve projecting through the mount radially to the 125 gage-glass, a shaft parallel to the glass, bearings for the shaft and arms operatively connecting the spindles of the valves with the shaft so that when the outlet-valve is closed the inlet-valves are held open, as set forth.

6. In a water-gage for a boiler the combination of a gage-glass, mounts for the ends of the gage-glass each having an inlet communicating with the interior of the glass and the boiler, a valve controlling each inlet and adapted to close against the passage of fluid from the boiler, a spindle to each valve projecting through the mount, means to prevent leakage between the spindle and the mount, 5 a valve controlling an outlet from the gage-glass, the valve being adapted to close against pressure within the glass, a spindle to this valve, a shaft, arms operatively connecting the spindles of the valves with the shaft so that when the outlet-valve is closed the inlet-valves are held open, and means for operating the shaft carrying the arms independently of the pressure in the gage-glass, as set forth. 10
7. In a water-gage for a boiler the combination of a gage-glass, mounts for the ends of the gage-glass each having an inlet communicating with the interior of the glass and the boiler, a valve controlling each inlet and adapted to close against the passage of fluid from the boiler, a valve controlling an outlet from the gage-glass the valve being adapted to close against pressure within the glass and presenting a greater area to the pressure within 15 the gage-glass than the sum of the area of the inlet-valves, and means for operatively connecting this valve with the inlet-valves so that when the outlet-valve is closed the inlet-valves are held open, as set forth. 20
8. In a water-gage for a boiler the combination of a gage-glass, mounts for the ends of the gage-glass each having an inlet communicating with the interior of the glass and the boiler, a removable barrel within each mount 25 interposed between the inlet of the mount and the gage-glass and open at one end toward the boiler, a valve adapted to close the open end of each barrel against the passage of fluid from the boiler, means of communication between the interior of each barrel and the gage-glass, a removable barrel interposed between 30 the interior of each barrel and the gage-glass and open at one end toward the gage-glass, a valve adapted to close the open end of the barrel against the passage of fluid from the gage-glass, means of communication between the interior of the barrel and the outlet, a spindle to the outlet-valve continued through the barrel and extended beyond the same, 35 means for preventing leakage between the spindle and its barrel and means for operatively connecting the spindle of this valve with those of the inlet-valves so that when the outlet-valve is closed, the inlet-valves are held open, as set forth. 40
9. In a water-gage for a boiler the combination of a gage-glass, mounts for the ends of the gage-glass each having an inlet communicating with the interior of the glass and the boiler, a valve controlling each inlet and adapted to be closed against the passage of fluid from the boiler by the pressure of said fluid, a valve controlling an outlet from the gage-glass said valve being adapted to close 45 against pressure within the glass and means for operatively connecting this valve with those which control the inlets so that when the former is closed the latter are held open, as set forth. 50

In testimony whereof I have signed my name to this specification in the presence of two subscribing witnesses.
